Application November 25, 1935, Serial No. 51,382
Renewed March 3, 1938

18 Claims. (Cl. 137—69)

Our invention is concerned with vacuum breakers for use with flush valves, etc., of the type shown in the patent to William C. Shanley, No. 2,087,049, granted July 13, 1937, in which the pipe between the valve and the bowl or similar member is provided with an air inlet to prevent back-siphonage, and a valve cooperating therewith to prevent the possibility of any water being forced outward through the air inlet during the flushing operation, as may tend to occur where the back-pressure is unusually high.

In the vacuum breaker shown in the aforesaid Shanley application, the valve and its casing are located outside of and to one side of the pipe, 15 making an asymmetrical structure and one in which the valve casing protrudes so that it is likely to be accidentally struck and possibly knocked off. In our improved construction the member carrying the inlet takes the form of 20 annulus with the axis of the pipe as a center, so as to prevent any objectionable projections, and the valve is preferably held open by gravity instead of closed, as in the aforesaid Shanley vacuum breaker.

25 To illustrate our invention we annex hereto two sheets of drawings in which the same reference characters are used to designate identical parts in all the figures, of which—

30 Fig. 1 is a side elevation of a flush valve with our vacuum breaker applied thereto.

Fig. 2 is a central vertical section of the vacuum breaker on an enlarged scale.

Fig. 3 is a portion of a similar view but with the parts shown in their non-flushing position.

35 Figs. 4, 5 and 6 are horizontal sections on the lines 4—4, 5—5, and 6—6 of Figs. 2 and 3.

As usual, the supply pipe 10 to be protected 40 opens into a flush valve 11, which may be of any desired construction, operated by the handle 12 and having the outlet 13 upon which is screwed the inlet member 14 by the connection 15, preferably integral with the body portion 16 which has its internal cross section tapered, as seen at 17, to produce a nozzle effect as shown in the 45 vacuum breaker of the Shanley application No. 6,761 filed February 15, 1935, upon which our invention in some respects may be considered to be an improvement. The casing member 18 is in the form of a generally cylindrical shell with the inwardly and downwardly inclined flange portion 19 forming a reduced outlet 20 of an area slightly larger than that of the nozzle outlet 28. Its lower end is externally threaded so 50 that the threaded connection 22 may be used to secure the flanged upper end of the pipe 23 to

said end with the gasket 24 interposed in the customary manner.

The upper end of the casing 18 is secured to the inlet member by the annulus 24' which is externally threaded to screw into the top of 5 the casing 18, and internally threaded to screw onto the reduced portion 25 of the inlet member 14. The annulus 24' is preferably sweated or otherwise permanently secured upon the member 14. The air inlets 26, preferably four in number 10 and of the shape shown in Figs. 2 and 4, extend through the annulus 24' and are protected from the entry of anything except air by the skirt 27 preferably formed integrally with the member 14 and extending over the inlets 26, and thence 15 downwardly.

What may be considered as added features to the structure of the vacuum breaker of the aforesaid Shanley application No. 6,761 will now be described. Instead of having the nozzle integral for its entire length, the lower part 28 is formed of a separate tube, preferably with the vertical ribs 29 on its exterior and with its upper end threaded into the annulus 24' and contacting the portion 25 to form a continuous outlet. 25 Ears 30 project from the lower end of the part 28, and pivoted on the ears are the hinged portions 31 of the flaps 32, preferably two in number, by the pins 33, which are loosely mounted in the apertures of the ears 30 and the portions 31 30 so that there can never be any danger of binding due to corrosion or possible impurities in the water. To insure the pins 33 remaining in place, we, as seen in Fig. 5, make them so long that their ends almost contact with the casing 18. 35 The hinged portions 31 are shaped, as seen in Figs. 2 and 3, so as to cooperate with the annular valve member 34 which preferably has the rubber seat 35 set in its upper portion to cooperate with the annular seat formed by the annular ribs 40 36 projecting downwardly from and forming the bottom of an annular channel 37 in the annulus 24' and extending to the air inlets 26. The ribs 29 guide the member 34 and reduce any possible friction. As seen in Fig. 5, the semi-annular 45 flaps 32 do not quite meet at their edges so that a passage for air from the outside up through the inlet member 14 always exists when the valve 11 is not in operation, and the weight of the annulus 24 resting on the hinged members 31 50 holds them closed, as seen in Fig. 3. Instead of leaving a passage between the flaps, we might form one or two small apertures therethrough, as indicated in dotted lines at 38 in Fig. 5. When, however, the flushing occurs, as indicated in Fig. 55

2, the flow of the water swings the flaps 32 to the position shown, and the hinged members 31 lift the annulus to the position shown, sealing the air inlets 26 and preventing the possibility of any water being forced out through them by back pressure, no matter how strong.

5 While we have shown and described our invention as embodied in the form which we at present consider best adapted to carry out its purposes, 10 it will be understood that it is capable of modification, and that we do not desire to be limited in the interpretation of the following claims except as may be necessitated by the state of the prior art.

15 What we claim is new, and desire to secure by Letters Patent of the United States is:

1. In a vacuum breaker, the combination with a chamber having an outlet through which a liquid is discharged at intervals, of a nozzle extending thereinto well toward the outlet, a flap held by gravity against the outlet of said nozzle when there is no discharge of the liquid, an air inlet to said chamber concentric with the nozzle, and a valve member cooperating with the air 20 inlet controlled by the flap.

2. In a vacuum breaker, the combination with a chamber having an outlet, of a nozzle extending thereinto well toward the outlet, a pair of flaps pivoted on the nozzle and held by gravity against the end of the nozzle, an air inlet to said chamber concentric with the nozzle, and a valve member 25 cooperating with the flaps and moved thereby to engage the inlet.

3. A vacuum breaker as defined in claim 1 in which the valve member holds the flap to the nozzle.

4. A vacuum breaker as defined in claim 1 in which the flap is pivoted to the nozzle and the valve member rests on a portion of the flap to 40 hold it normally to the nozzle outlet.

5. A vacuum breaker as defined in claim 1 in which there are a pair of flaps pivoted to the nozzle substantially closing its outlet and the annular valve member rests on portions of the flaps.

45 6. A vacuum breaker as defined in claim 1 in which the air inlet is located in an annulus connecting the tops of the chamber and the nozzle.

7. A vacuum breaker as defined in claim 1 in which there are a plurality of arcuate air inlets in an annulus connecting the tops of the chamber 50 and the nozzle.

55 8. A vacuum breaker as defined in claim 1 in which a plurality of arcuate air inlets are located in an annulus connecting the tops of the chamber and the nozzle and the valve member is an annulus beneath the inlets and rests directly on portions of the flaps to hold them against the nozzle outlet.

9. A vacuum breaker as defined in claim 1 in which there are a pair of flaps pivoted to the nozzle substantially closing its outlet, and in which there are a plurality of arcuate air inlets located in an annulus connecting the tops of the chamber and the nozzle and the valve member is an annulus beneath the inlets resting directly on portions of the flaps to hold them against the nozzle outlet.

10. In a vacuum breaker, the combination with 10 a cylindrical chamber having an outlet at its bottom, of a nozzle let into the top thereof and extending towards its outlet and concentric therewith, an apertured annulus connecting the top of the chamber and the upper part of the 15 nozzle, a flap cooperating with the outlet of the nozzle, and an annular valve member surrounding the nozzle and located between the flap and the apertured annulus and moved by the former to engage it with the latter.

20 11. A vacuum breaker as defined in claim 10 in which there are a pair of flaps pivoted to the bottom of the nozzle.

12. A vacuum breaker as defined in claim 10 in which there are a pair of flaps pivoted to the bottom of the nozzle and the annular valve member normally rests directly on portions of the flaps.

25 13. A vacuum breaker as defined in claim 10 in which there are a pair of flaps loosely pivoted to the bottom of the nozzle by pins passing loosely 30 through the pivotal portion of the flaps and ears on the nozzle and extending to the inner wall of the chamber.

14. A vacuum breaker as defined in claim 10 in which there are vertical ribs interposed between 35 the exterior of the nozzle and the interior of the annular valve member to position the latter and to reduce friction.

40 15. A vacuum breaker as defined in claim 10 in which there are vertical ribs on the exterior of 40 the nozzle to position the annular valve member and to reduce friction.

16. A vacuum breaker as defined in claim 10 in which there is a skirt extending from the top of the nozzle over the apertured annulus and thence 45 downward.

17. A vacuum breaker as defined in claim 10 in which the nozzle is composed of two parts with the lower part having the flap pivoted thereto and with the upper part threaded to the apertured annulus.

50 18. A vacuum breaker as defined in claim 10 in which the apertured annulus has a pair of annular members projecting downwardly from its under side forming a valve seat with which the 51 annular valve member cooperates.

AUGUST C. DOBRICK.
RALPH A. TANK.
